UNITED STATES PATENT OFFICE.

JOSEPH SHOWALTERBAUGH, OF GARY, INDIANA.

REVERSIBLE TURBINE-ENGINE.

1,384,976.

Specification of Letters Patent. Patented July 19, 1921.

Application filed November 27, 1920. Serial No. 426,740.

To all whom it may concern:

Be it known that JOSEPH SHOWALTERBAUGH, a citizen of the United States, residing at Gary, in the county of Lake and State 5 of Indiana, has invented certain new and useful Improvements in Reversible Turbine-Engines, of which the following is a specification, reference being had therein to the accompanying drawing.

10 The invention relates to reversible turbine engines, and has for its object to provide a device of this character comprising a casing having removable heads, in which heads a shaft is rotatably mounted and provided 15 with a plurality of turbine wheels, said turbine wheels being driven by projected steam, which is projected into pockets on the turbine wheels, said steam being projected from substantially tangentially disposed 20 nozzles; also to mount said nozzles on rockable shafts, rockably mounted in bearings of the detachable heads, said shafts being provided with steam passages in communication with a steam manifold, carried by one of the 25 detachable heads, the other ends of said rockable shafts being provided with gears meshing with a gear ring rotatably mounted in one of the detachable heads and rotated by a worm for rotating the gear ring and reversing the tangential positions of the steam 30 projecting nozzle.

A further object is to provide the rockable nozzle shafts with spaced nozzles, between which nozzles the turbine wheels are disposed, said turbine wheels being provided 35 with a plurality of pockets on the sides thereof and adjacent their peripheries and in registration with the nozzles.

40 A further object is to construct the detachable heads and the casing so that the interior of the engine will be readily accessible and the turbine wheels may be easily and quickly removed without disassembling the entire engine.

45 A further object is to form the side pockets in the turbine wheels, by cutting transversely disposed slots after a circumferential groove has been cut in the periphery of the wheel, then placing in the circumferential groove an annular member for dividing the transversely disposed slots into 50 pockets, said pockets being closed at their outer ends by an annular band which may be shrunk or otherwise secured on the periphery of the wheel.

With the above and other objects in view

the invention resides in the combination and arrangements of parts as hereinafter set forth, shown in the drawings, described and claimed, it being understood that changes in 60 the precise embodiment of the invention may be made within the scope of what is claimed without departing from the spirit of the invention.

In the drawings:—

65 Figure 1 is a side elevation of the intake side of the engine.

Fig. 2 is a vertical sectional view taken on line 2—2 of Fig. 1.

70 Fig. 3 is a side elevation of the nozzle controlling side of the engine, parts being broken away to better show the structure.

Fig. 4 is a vertical sectional view taken on line 4—4 of Fig. 2.

75 Fig. 5 is an enlarged detail perspective view of the portion of one of the turbine wheels, showing the pocket construction.

Referring to the drawings, the numeral 1 designates a casing of the engine which comprises the cylindrical body portion 2 80 which is provided with outwardly extending annular flanges 3 at its ends. Secured to the ends of the body portion 2 of the casing by bolts 4 is an intake manifold head 5 and a removable head 6. Head 5 is provided 85 with an annular manifold 7 having removable plugs 8 at spaced points thereon and by the removal of which access may be had to the interior of the manifold, and for placing in position and removing the rockable 90 nozzle shafts 9, which have one of their ends rockably mounted in bearings 10 of the head 5, and held in said bearings by nuts 11 having interposed between the same and the head, spring washers 12. Nozzle shafts 9 95 extend through bearings 13 in an annular flange 14 carried by the inner periphery of the cylindrical body portion 2 of the casing and are provided with reduced portions rockably mounted in bearings 15 of the removable head 6 and are held against axial movement therein by means of nuts 16 having interposed between the same and the head spring washers 17. Spring washers allow a slight axial movement of the rockable shafts 9, the purpose of which will 100 presently appear. Secured to the ends 18 of the rockable shafts 9 are gears 19, which gears are concentrically disposed and mesh with the gear teeth 20 of a rotatable gear 110 ring 21. Gear ring 21 is rotatably mounted on the periphery of the flanged extension 22,

carried by the head 6 and is provided with an annular flange 23 which overlies the outer side of the flanged extension 22, which flanged extension prevents axial movement 5 of the gear ring 21 inwardly and maintains the gears 19 in mesh with the gear teeth 20. Axial movement of the gear ring 21 outwardly is prevented by the removable gear casing ring 24, which ring is secured at its 10 inner edge to the flanged extension 22 by means of bolts 25 and to the flanges 3 by means of the bolts 4 which pass through flanges of the gear casing ring and apertures in the removable head 6 and the flange 15 3, at the end of the cylindrical casing 2. Gearing 21 adjacent its outer side is provided with gear teeth 26, which gear teeth mesh with a worm 27 rotatably mounted in bearings of the gear casing ring adjacent the 20 lower side thereof. Worm 27 is carried by a shaft 28 which may be operated in any suitable manner for rotating the gear ring 21. When the gear ring 21 is rotated, it will be seen that through the gears 19, the 25 rockable shafts 9 will be simultaneously rocked.

Rockable shafts 9 are provided with chambers 29, one end of which chambers is in communication with the steam manifold 7 so 30 that steam which enters the manifold 7, through steam supply pipes 30, will enter the chambers 9. Rotatably mounted in bearings 31 of the head 6 and bearings 32 of the head 5 is a shaft 33, on which shaft turbine wheels 34 are secured. Bearings 31 and 32 and the shaft 33 are so constructed that the heads 5 and 6 may be removed after the nuts 11 and spring washers 12 have been removed, thereby allowing access to either side of the engine 35 without disassembling the entire engine.

Turbine wheels 32 have their outer edges disposed between steam projecting nozzles 35 carried by the rockable shafts 9 and are provided with side pockets 36 and into which 40 pockets the nozzles 35 project the steam thereby causing the turbine wheels 34 to rotate. By referring to Fig. 4 it will be seen that when the turbine wheels 34 are revolving in the direction of the arrow *a* that the nozzles 35 are substantially tangentially disposed.

It will also be seen that when it is desired to reverse the direction of rotation of the turbine wheels 34, that it will only be necessary to revolve the shaft 28 which will cause the rotation of the gear ring 21 with which gear ring the pinions 19 mesh. This action will cause the pinions 19 and the rockable shafts 9 to rotate partially, thereby causing the nozzles 35 to assume a substantially 55 tangential position opposite to that shown in Fig. 4 in relation to the pockets 36 of the turbine wheels, which will cause a reverse rotation of the turbine engine.

The pockets 36 are formed by first forming 60 a circumferential channel in the periphery of

the turbine wheels, then slotting the periphery of the wheel transversely, after which an annular strip 37 is placed in the circumferential channel of the wheel. Annular strip 37 will divide the transversely disposed 70 slots into side pockets 36. However to close the outer end of the pockets 36 an annular band 38 is placed on the periphery of the wheel and preferably held thereon by shrinking the same into place while hot, or in any 75 other suitable manner.

The ends of the rockable shafts 9 are preferably mounted in the movable flanged bearing sleeves 39, thereby allowing enlarged apertures in the removable heads 5 and 6 80 so that none of the rockable shafts 9 will interfere with the removal of the head 5 or 6 which is being removed, that is, after the nut 11 and spring washer 12, or the nut 16 or spring washer 17 have been removed. 85 After a head has been removed and it is desired to remove one of the turbine wheels 34, the shafts 9 are rocked until the nozzles 35 are positioned beyond the periphery of the turbine wheel desired to be removed, at 90 which time the turbine wheel can be moved outwardly and replaced by another, or repaired and replaced.

From the above it will be seen that a turbine engine is provided, which may be easily 95 and quickly reversed, and one which is simple in construction, the parts easily removed from the interior thereof without disassembling the machine and one which is positive in its operation.

One end of the shaft 33 is provided with a pulley 39, to which pulley machinery may be belted if so desired, for instance a dynamo.

Steam is exhausted from the casing 1 105 through the exhaust pipes 40, which may lead to any suitable place desired.

The invention having been set forth what is claimed as new and useful is:—

1. A turbine engine comprising a casing 110 having rotatably mounted therein a turbine wheel having pockets in its side, a rockable shaft rockably mounted in the casing adjacent the periphery of the turbine wheel and provided with a steam supply chamber, a steam projecting nozzle carried by said rockable shaft and disposed substantially tangential to the pockets and means for rocking the shaft for reversing the position of the nozzle when it is desired to reverse the direction of rotation of the turbine wheel.

2. The combination with a turbine engine comprising a casing having rotatably mounted therein a turbine with pockets in its sides adjacent its periphery, of a rockable chambered shaft rockable in the casing and adjacent the periphery of the wheel, spaced steam projecting nozzles carried by the shaft and disposed on each side of the wheel and substantially tangential in relation to the 115 120 125 130

pockets and means for rocking the shaft for reversing the tangential position of the nozzles.

3. The combination with a turbine engine comprising a casing having rotatably mounted therein a turbine wheel with pockets in its sides adjacent its periphery, of a rockable shaft having a steam supplying chamber, said shaft being disposed adjacent the periphery of the turbine wheel and provided with spaced nozzles disposed to each side of the wheel and tangentially disposed in relation to the wheel pockets, and means for reversing the tangential position of the nozzles by rocking the shaft when it is desired to reverse the direction of rotation of the turbine wheel.

4. The combination with a turbine engine comprising a casing having rotatably mounted therein a plurality of turbine wheels with pockets in their sides adjacent their peripheries, of a plurality of rockable shafts rockably mounted in the casing and having steam supplying chambers therein, one end of said chambers being in communication with a steam manifold, spaced nozzles carried by the rockable shafts and disposed on each side of the turbine wheels and substantially tangentially disposed in relation to the pockets, said nozzles being in communication with the chambers of the rockable shafts, and means for simultaneously reversing the tangential positions of the nozzles for reversing the direction of rotation of the turbine wheels.

5. The combination with a turbine engine comprising a casing having rotatably mounted therein a plurality of turbine wheels with pockets in their sides adjacent their peripheries, of a plurality of rotatable shafts rockably mounted in the casing adjacent the peripheries of the turbine wheels and provided with steam supply chambers in communication with a steam manifold, nozzles carried by said rockable shafts and disposed to project steam tangentially into the pockets of the wheels, gears carried by one end of said shafts, said

gears meshing with a gear ring and means for rotating said gear ring for simultaneously reversing the positions of the nozzles.

6. A turbine engine comprising a casing having removable heads, a shaft mounted in bearings of said heads and provided with turbine wheels having pockets in their sides adjacent their peripheries, a plurality of rockable shafts having steam chambers therein, said shafts being rockably mounted in bearings of the removable heads, a steam supply manifold carried by one of the heads and in communication with the chambers of the rockable shafts, a gear ring rotatably mounted in one of the removable heads and meshing with gears carried by the rockable shafts, nozzles carried by the rockable shafts and tangentially disposed in relation to the wheel pockets and means for rocking the gear ring for simultaneously reversing the position of the nozzle.

7. The combination with a turbine wheel of a turbine engine, said wheel having pockets on its sides, of projecting nozzles carried by a rockable shaft having a steam supply chamber for said nozzles, and means for rocking the rockable shaft for reversing the position of the nozzles.

8. The combination with a turbine wheel having pockets in its side, of a projecting nozzle carried by a rockable shaft having a steam supply chamber, and means for reversing the position of the nozzle in relation to the pockets of the wheel when it is desired to reverse the direction of rotation of the wheel.

9. The combination with a turbine wheel, of a turbine engine having pockets in its sides, of steam projecting nozzles carried by rockable shafts having steam supply chambers therein, of means for simultaneously reversing the positions of the nozzles for reversing the direction of rotation of the turbine wheel.

In testimony whereof I hereunto affix my signature.

JOSEPH SHOWALTERBAUGH.
